WEATHER STRIP

Elmer D. Barringer, Cleveland, Ohio

Application September 7, 1933, Serial No. 688,523

20 Claims. (Cl. 20—69)

This invention appertains to concealed weatherstrip constructions primarily adapted for use in door and casement window installations wherein it is desired to effectively seal a swingable closure member in its cooperating frame.

In the usual and known types of weatherstrip constructions, considerable difficulty is encountered in maintaining a good seal after a short time of use following the installation of the weatherstrip, even though the seal may be adequate at first. Shrinkage and warping of the sashes and/or frames tends to misalign the weatherstrips or otherwise subjects them to strains so that the sealing effect is materially reduced if not wholly destroyed. Under some conditions the misalignment or distortion of the weatherstrips becomes so great that the door or window cannot be completely closed or may be closed or opened only with great difficulty owing to the excessive friction or sticking or jamming of the parts. It not infrequently occurs that the shrinkage above referred to, or the operation of the members when the weatherstrips are for some reason distorted or misaligned, causes the weatherstrips to pull loose on their nailings.

In addition to the foregoing, the construction of many types of weatherstrips is such that even under normal and most favorable conditions, considerable friction must be overcome in opening and closing the door or window, thereby detracting from their practicability and usefulness even though the sealing afforded thereby may be excellent.

With the foregoing in mind, I have aimed to provide a weatherstrip construction which is self-adjusting to automatically accommodate shrinkage and warping conditions of the members with which the weatherstrip is associated; and further, which enhances the smoothness and ease of action of the sash in opening and closing movements.

To the end of reducing friction and the possibility of sticking to a minimum, I have provided a weatherstrip of such configuration that it tends to move the sash toward open position as soon as the lock or latch devices which secure the sash in closed position in its frame, are released, thereby actually assisting in the opening movement of the sash.

The invention has for a further object the provision of a weatherstrip embodying a sealing strip or flange arranged for effecting a weatherproof seal through edgewise contact of the free edge of the flange, the flange being suitably carried on the frame so as to afford free lateral

movement of the flange, enabling an automatic positioning of the same when the sash is closed, and the free edge of the flange being normally out of sealing contact as when the sash is open, but the flange being swingable about an axis 60 extending longitudinally with respect thereto so as to bring said free edge into such sealing contact when the sash is closed.

A still further object of the invention is to provide a weatherstrip in the form of one or more 65 folds of resilient material, one fold being provided with an outwardly diverging sealing flange, and this fold being mountable in inverted relation to the member to which the weatherstrip is applied so that the free edge of the sealing flange 70 constitutes the sealing edge.

Another object of the invention is to provide a 75 weatherstrip which is simple and easy to install and which minimizes likelihood of becoming damaged or permanently distorted when exposed to accidental impacts or pressure of extraneous bodies as when the door or window is left in open position for substantial periods of time.

Other and further objects and advantages of the invention will become apparent from the following description and the novel features thereof defined by the appended claims.

In the drawings—

Figure 1 is a fragmentary perspective view of 85 a casement window construction embodying one form of my weatherstrip, and particularly showing the top or head strip construction.

Figure 2 is a sectional view taken on a plane 90 extending through a casement window or door construction at right angles to the axis of swing, which construction has my invention embodied therein, and particularly showing the weatherstrip constructions for the lock and hinge sides thereof, the window or door being shown closed.

Figure 3 is a view similar to Figure 2, with the 95 weatherstrip parts in the positions normally assumed when the window or door is open as shown.

Figure 4 is an enlarged fragmentary detail sectional view of one form of my weatherstrip construction particularly applicable for use on the head and lock sides of a door or window.

Figures 5, 7, 9, and 10 are views similar to Figure 4, showing various modified forms of weatherstrip constructions particularly applicable to the 105 hinge sides of a window or door construction.

Figures 6, 8, and 11 are views similar to Figure 4, showing various modified forms particularly applicable to the head and lock sides.

Figure 12 is a perspective detail view of one 110

form of one sealing element of a weatherstrip constructed according to my invention.

Figure 13 is a perspective detail view of a modified form of the element shown in Figure 12.

5 Figures 14, 15, and 16 are fragmentary perspective detail views of various forms of elements adapted to interlock or otherwise coact with the elements shown in Figures 12 and 13.

10 Figure 17 is a fragmentary perspective view of one end of a member as shown in Figure 12, certain of the sides of the folds being provided with flaps or rearwardly bent extensions serving as deflectors for directing water toward the outside at the bottom of a window or door.

15 Figure 18 is an enlarged fragmentary detail view similar to Figure 4, showing the positions normally assumed by the weatherstrip parts as on the lock side when the sash is swung open.

20 Figure 19 is a view similar to Figure 2, but showing a double casement window or door construction, the weatherstrips for the hinge sides being omitted.

25 Figure 20 is an enlarged fragmentary detail view of the meeting stiles of the construction of Figure 19, showing the weatherstrip arrangement as applied to such meeting stiles.

30 Figure 21 is a view taken approximately on the line 21—21 of Figure 20 in the direction of the arrows.

35 Figure 22 is a fragmentary perspective view of an escutcheon plate for the double casement constructions of Figures 19 and 20.

40 It is to be understood that while the invention is particularly described and shown in its application to casement window constructions, it is not confined thereto since it is equally applicable to doors or any closure construction embodying a member swingably mounted for cooperation with a frame or other member with which a sealing relation is to be established. The axis of swing may obviously be either vertical, horizontal, or otherwise. Nor is the invention confined to use with swingable closures since under some conditions and in certain forms shown and 45 described, it may be applied to the usual sliding type of windows or double-hung windows, in which event the novel construction of my strip serves excellently to prevent rattling of the window.

50 Like reference characters designate corresponding parts in the several figures of the drawings.

55 Referring first to Figures 1 to 4 and 18, there is shown a window frame generally denoted by the reference character 1, embodying a jamb 2 and a stop 3 with which the window sash, generally designated 4, is adapted to cooperate when in closed position. Suitable hinges 5 are employed to swingably mount the sash 4 in the frame for opening preferably in an inward direction. It will be understood that the sash and frame is of the usual construction.

60 The free edge of the sash, that is the lock side, designated 6, is rabbeted at 7 to receive one of a pair of interlocking weatherstrips which are to be arranged to seal the free edge of the sash relatively to the frame. In one form, this member which is to be mounted in the rabbeted portion comprises a reversely bent or folded strip 8 affording a first fold or tongue 9, and a second fold 10' affording a substantially U-shaped channel 10. Attaching flanges 11 and 12 are provided by means of which the strip may be nailed or otherwise secured in position.

65 The member which is to cooperate with the 75 reversely bent member 8 is applied to the jamb

2, and in one form comprises a reversely bent or folded strip generally designated 13, providing a first fold 14' affording a substantially U-shaped channel or groove 14 for receiving the tongue 9 of member 8, and a second fold 15' having a sealing flange 15 which is angularly offset in an outwardly diverging direction for purposes to be hereinafter described. A laterally offset attaching flange 16 is provided for the member 13 by means of which the member may be secured to the jamb by nails or in any other suitable manner. It will be observed that in applying the strip 13 to the frame, the same is positioned so that the first fold 14' is located against or in close proximity to the inner surface 17 of the stop 3. The free edge of the outwardly diverging sealing flange 15 normally terminates in slightly spaced relation to the surface 17 when the member 13 is applied to the frame in the manner described. In other words, the sealing flange 15 does not project as far forwardly as does the bend forming the channel 14 so that when the member 13 is applied to the frame, the free edge of the sealing flange will not engage the stop.

80 In closing the window to which has been applied the member 8, the tongue 9 will be pressed into the channel 14 of member 13, and the groove or channel 10 of member 8 receives and encompasses the second fold of member 13 including the sealing flange 15. As this takes place, the 85 folds and sealing flange 15 may move in either direction laterally, owing to the lateral offsetting of the attaching flange 16, depending upon which sides of the folds interengage first, thereby accommodating and automatically adjusting the 90 parts regardless of misalignments or deformations due to shrinkage and warpage of the sash or frame. As the sash reaches its final closed position within the frame, the member 8 near the corner 18 presses against the sealing flange 15 95 slightly rearwardly of the free edge of the sealing flange and brings the free edge 19 into sealing engagement with the surface 17 of the stop 3. A seal is thereby effected between the sealing flange and the stop of the window frame, as 100 well as between the flange and the sash, the former occurring at the line of contact of the free edge 19 with the surface 17 of the stop, and the latter occurring at the line of contact between the sealing flange and the cooperating 105 sealing member 8 carried by the sash. Thus, air, rain, snow, dust, and other foreign matter is effectively excluded and prevented from entering between the window frame and the sash.

110 The member 8 may be formed of any suitable 115 material which is relatively stiff and substantially rigid so that it will hold its shape. The cooperating member 13 is preferably formed of resilient material, such as spring bronze of the type customarily employed in metal weatherstripping practice. It is this latter member which permits of the automatic adjustment of the interlocking strips, the fold carrying the sealing flange 15, being yieldably movable laterally.

120 As has been mentioned above, the free edge 19 of the sealing flange 15 is normally spaced from the surface 17 of the stop 3, that is, when the sash is opened so as to disengage member 8 from member 13 (shown best in Figure 18). In bringing this 125 free edge into sealing contact with the surface 17, the sealing flange 15 swings on an axis extending longitudinally relatively to the strip, folds 15' and 14' resiliently resisting the movement of the flange to bring the free edge 19 into sealing contact with the surface 17. As shown, the seal- 130

ing flange 15 begins to diverge outwardly at 20, which is preferably slightly forward of the base of the second fold of member 13, thereby giving to the sealing flange a somewhat greater angle of divergence to insure positive sealing contact of the free edge 19 under the influence of the portion of member 8 contacting with the flange when the window is closed. This angle of offset or divergence is such that it materially assists in opening the window. As soon as the usual lock or latch (not shown) for the window is released, the resisting pressure of the sealing flange tends to start the motion of the window in an outward direction; that is, in an opening direction, so that the member 8 starts to disengage from member 13. Conversely, in closing the window, the last part of the closing movement may be effected by the window lock or latch which will positively force or cam the member 8 into engagement with member 13 and bring about the positive sealing contact of the free edge 19 with the surface 17. With the free edge 19 in such sealing contact, there will be exerted a yieldable pressure through the sealing flange 15 in a direction substantially normal to surface 17, which resilient pressure is created by the inter-engagement of members 8 and 13.

From the foregoing it will be clear that the essential feature of member 13 is a fold 15' which is relatively inverted with respect to one surface with which it is to cooperate for sealing purposes, the fold including an outwardly diverging or angularly inclined sealing flange, the free edge of which is normally spaced from said surface but capable of being brought to sealing contact therewith by the application of pressure on said sealing flange. The use of an additional fold laterally spaced and reversely extending with respect to the inverted fold, while not being necessary, gives greater flexibility of movement and efficiency in action.

This arrangement also minimizes likelihood of distortion or damage of the strip 13 by accidental impacts or blows to which it might be subjected when the window is in an open position, so as to expose this member. The reversely extending folds are capable of withstanding considerable pressures without producing permanent distortion.

To minimize the likelihood of sticking or locking of the free edge 19 of the sealing flange 15 when the same is pressed into contact with the surface 17, the free edge may be rebent on itself as at 21. This rebending also produces a stiffening of the sealing edge so as to insure good sealing contact. Similarly, the free edge of attaching flange 16 may be rebent on itself as at 22 to stiffen this edge and to produce an effective sealing contact with the jamb when the flange is attached thereto. In using this construction, fewer nails or other securing devices will be necessary in applying the member 13 to the jamb so that the attaching flange will be maintained perfectly flat and in good sealing contact with the jamb.

The construction of members 8 and 13, as above described, may be followed for sealing the upper edge or head of the window as shown clearly in Figure 1.

Referring now to the hinge side of the window as shown in Figures 2, 3, and 5, the sash may be rabbeted at 23 in a manner similar to the rabbet 7 on the free edge, and the sealing member 8 applied thereto, as hereinabove described. The cooperating sealing member embodies an inverted fold 15' including the outwardly diverging sealing flange 15, constructed entirely similar to the outer

portion of sealing member 13 for the lock side of the window, except that fold 14' is omitted. Attaching flange 24 is provided for fold 15' so as to extend laterally therefrom for application to the jamb of the frame. For this hinge side installation, the free edge 19 of the sealing flange 15 is arranged for sealing contact with the jamb instead of the stop, the free edge however being normally out of contact with the jamb when the window is in open position. As the window is closed, fold 15' is automatically guided into the channel formed by fold 10' of member 8, and tongue 9 of member 8 engages sealing flange 15 so as to press the free edge 19 of flange 15 into sealing contact with the jamb during the final closing movement of the window, the operation being similar to that described with relation to the engagement and disengagement of the sealing members on the lock and head sides of the window.

The sealing member which is applied to the sash at the lock and head sides, may have other forms than that of member 8, hereinbefore described. As shown in Figure 6, the construction is the same except that the attaching flange 11 of member 8 in Figures 1 to 4 and 13 is omitted, the application of the sealing member to the sash being made entirely by the attaching flange 12. The cooperating member shown in Figure 6 is the same as member 13 described in the preceding figures. Figures 8 and 15 show a further modified form of member 8 which may be employed on the lock and head sides of the sash, this modification omitting the second fold 10' of member 8, hereinbefore described, and embodying solely the first fold or tongue 9 and attaching flange 12, cooperating member 13 being the same. A still further modification of member 8 is shown in Figures 11 and 16 in which it has the form of a lapped strip providing a tongue 9', the free sides of the lap forming a double attaching flange 12'. Member 13 remains the same in this construction and cooperates with tongue 9' in a manner which will be clearly apparent from the drawings. In the modifications of Figures 8 and 11, the rabbeted corner of the sash, as at 25, is brought to bear on the sealing flange 15 to effect sealing contact of the free edge 19 of the sealing flange with surface 17 of stop 3.

Figure 7 shows a modified construction for the hinge side of the window wherein a single weatherstrip sealing element is employed, this element having the same form as that shown on the hinge side in Figures 2, 3 and 5. In such a modified installation the inverted fold is reversed with respect to the position shown in Figures 2, 3 and 5 so that the attaching flange 24 extends in the opposite direction for insertion into a kerf 26 cut in the corner of the frame formed by the stop 3 and jamb 2. The hinge side of the sash is rabbeted at 23' to receive the inverted fold and cooperates therewith to effect a seal in a manner which will be fully apparent from the drawings taken in conjunction with the description of the operation of the various modifications hereinbefore described. In this construction of Figure 7, the sash need not be provided with any interlocking sealing element since the rabbet 23' serves as the means for producing the sealing action.

Figures 9 and 10 show constructions similar to the hinge side of Figures 2, 3 and 5 except that the sealing elements applied to the sash are similar to the elements shown on the lock side in Figures 8 and 11, respectively.

Referring now to Figures 19 to 22, there is

80

120

125

130

135

140

145

150

shown an arrangement suitable for application to double casements, the meeting stiles of the casements 27 and 28 being provided with the sealing elements in a manner similar to the previously 5 described installations, for single casements. One stile is suitably rabbeted as at 29 for the application thereto of a member conforming to member 8 of Figures 1 to 4 and 18. The cooperating member applied to stile 27 is similar to member 10 member 13 except that the attaching flange is bent over as at 30 for the attachment of the member to the stile. An escutcheon 31 is secured to one of the stiles as by screws 32 and serves to provide a surface against which the free edge of the sealing 15 flange of member 13 is adapted to be brought into sealing contact so as to exclude water, dust, etc. The escutcheon is shown in greater detail in Figures 21 and 22.

In Figure 17 there is shown a sealing member 20 conforming to member 13 of Figures 1 to 4 and 18, the end of member 13 being cut to provide upwardly bent flaps or extensions 33 and 34. This Figure has particular reference to the formation of the lower ends of members 13 when applied 25 to the vertical sides of the window frame. The lower side of the lower edge of the window in practice would generally have associated therewith a self-draining type of weatherstrip of conventional form, such a weatherstrip being shown 30 in Figure 1. By suitably forming the lower ends of the weatherstrips applied to the hinge and lock sides of the window, as shown in Figure 17, water which may collect within the folds of member 13 will be deflected outwardly or toward the 35 weather side of the window between the bottom of the sash and the conventional self-draining channel.

The operation of my improved weatherstrip should be apparent from the foregoing description 40 taken in conjunction with the illustrations of the drawings, and it will be apparent that there is provided a weatherstrip which is simple in construction but positive in action, eliminating many of the common difficulties encountered in 45 the usual constructions.

While the specific details of construction have been herein shown and described, it is to be understood that the invention is not to be confined thereto since changes and alterations may be 50 made without departing from the spirit thereof as defined by the appended claims.

Having thus described my invention, what I 55 claim as new and desire to secure by Letters Patent of the United States, is—

1. In a window construction or the like including a relatively stationary member and a relatively movable member, a flexible sealing member intermediate the stationary and movable members, the said flexible sealing member comprising a flange 60 adapted to be engaged by the relatively movable member to form a seal therewith and to contact with the relatively stationary member to form a seal with the latter member.

2. A weatherstrip for closures and the like embodying relatively stationary and movable members, comprising a strip of resilient material having a fold, one side of said fold being attachable to one of said members and the other side of said fold being free to move laterally, said strip being mountable intermediate said members with the laterally movable side of said fold normally spaced from its respective member but engageable with its respective member, and the other member, to 75 effect a seal between said members incident to

relative movement of said members to closed position.

3. A weatherstrip for closures and the like embodying relatively stationary and movable members, comprising a reversely bent strip of resilient material, one side of which is attachable to one of said members to dispose the strip intermediate the members with the reversely bent portion freely movable laterally with respect thereto when said members are in relatively open position, the unattached side being engageable with the other member and having its free edge normally spaced from its respective member, said free edge being adapted to be pressed into contact with its respective member when the unattached side is engaged by the other member during relative closing movement of said members, the unattached side of said strip thereby serving as a self-adjusting sealing means for said members. 80 85

4. A weatherstrip of the class described comprising an inverted substantially U-shaped fold of resilient material, a portion of one side of said fold being outwardly inclined and the free edge thereof constituting a sealing edge, and an attaching flange on the other side of said fold. 90

5. A weatherstrip for a pair of members, one of which is relatively stationary and the other of which is relatively swingable, said weather strip comprising self-adjusting, interlocking sealing elements applicable one to each of said members, 95 one of said sealing elements having a pair of laterally spaced and reversely extending substantially U-shaped folds, the outer side of one fold being provided with an attaching flange, and the outer side of the other fold being provided with an 100 outwardly diverging sealing flange, the free edge of which is normally spaced from the respective member but capable of contacting therewith incident to the application of pressure on said sealing flange. 110 115

6. A weatherstrip for a pair of members, one of which is relatively stationary and the other of which is relatively swingable, said weatherstrip comprising self-adjusting, interlocking sealing elements applicable one to each of said members, 120 each of said sealing elements having a pair of laterally spaced and reversely extending substantially U-shaped folds, the outer side of one fold of each element being provided with an attaching flange, the outer side of the other fold of one element being provided with an outwardly diverging sealing flange, the free edge of which is normally 125 spaced from the respective member to which the sealing element is applied but is capable of contacting therewith incident to the application of pressure on said sealing flange, one fold of the other sealing element serving as a tongue and being adapted to be pressed into one fold of the cooperating sealing element, and the other fold of said other sealing element enveloping the second fold and diverging sealing flange of the cooperating sealing element and serving to press the free edge of said sealing flange into sealing contact with its respective member, the said sealing flange also affording sealing contact with the fold 130 of the other element by which it is enveloped. 135

7. A weatherstrip for a pair of members, one of which is relatively stationary and the other of which is relatively swingable, said weatherstrip comprising a sealing element adapted to be applied to one of said members and having an inverted fold, one side of said fold being provided with an outwardly diverging sealing flange, the free edge of which is normally spaced from its respective member to which the sealing element 145 150

- is applied but capable of contacting therewith incident to the application of pressure on said sealing flange, the other of said members having cooperating sealing means for receiving said fold and applying pressure to said sealing flange to press the free edge of said sealing flange into sealing contact with its respective member, the sealing flange also affording sealing contact with the sealing means of the other member.

8. A weatherstrip for relatively movable cooperating members of the class described, comprising a strip of resilient material, one edge of which is adapted to be applied to one of said members, said strip having a sealing flange extending in a plane substantially normal to one surface of the member to which it is applied with the free edge of said flange normally out of contact with said surface but engageable with said surface incident to the application of pressure to said strip by the other member to press said free edge into sealing contact with its respective member, the resiliency of said strip exerting a sealing pressure in a direction substantially normal to the surface with which the free edge contacts when in such sealing contact therewith.

9. A weatherstrip of the class described, comprising a member having a flexible resilient metal sealing flange, said flange being swingable about an axis extending longitudinally of said flange and being disposed for edgewise contact with the surface with which it is adapted to cooperate when so swung about said axis for sealing purposes, and the free edge of said flange being normally spaced from said surface.

10. In a window construction or the like including a frame, said frame having a stop, and a sash swingably mounted in said frame, the combination of a weatherstrip comprising a fold of resilient material, said fold being secured at one side to said frame so as to be laterally movable, the other side of said fold having an outwardly diverging sealing flange and the fold being inverted relatively to said stop with the free edge of said sealing flange normally spaced from said stop, said sash having means adjacent the free edge thereof for receiving the said fold and for applying pressure to said sealing flange to press the free edge of said sealing flange into sealing engagement with said stop, said sealing flange also affording sealing contact with said sash.

11. In a window construction or the like including a frame, a sash swingably mounted in said frame, the combination of a weatherstrip comprising a fold of resilient material, said fold being secured at one side to said frame so as to be laterally movable, the other side of said fold having an outwardly diverging sealing flange and the fold being inverted relatively to the said frame with the free edge of said sealing flange normally spaced from said frame, said sash having means adjacent one edge thereof for receiving said fold and for applying pressure to said sealing flange to press the free edge of said sealing flange into sealing engagement with said frame, said sealing flange also affording sealing engagement with said sash.

12. A weatherstrip for a pair of members, one of which is relatively stationary and the other of which is relatively swingable, said weatherstrip comprising cooperating self-adjusting, interlocking sealing elements applicable one to each of said members, one of said elements having a substantially U-shaped fold adapted to lie intermediate said members in spaced relation to the same so as to afford free lateral movement of

said fold, a second fold reversely extending relatively to said first fold and laterally spaced therefrom, the outer side of said second fold having an angularly offset portion normally disposed with the free edge thereof in spaced relation to the member to which said element is applied, said angularly offset side being resiliently yieldable and positioned to be engaged by the other member to press said free edge into sealing engagement with the member on which it is mounted.

13. A weatherstrip for a pair of members, one of which is relatively stationary and the other of which is relatively swingable, said weatherstrip comprising cooperating self-adjusting, interlocking sealing elements applicable one to each of said members, one of said elements having a substantially U-shaped fold adapted to lie intermediate said members in spaced relation to the same so as to afford free lateral movement of said fold, a second fold reversely extending relatively to said first fold and laterally spaced therefrom, the outer side of said second fold having an angularly offset portion normally disposed with the free edge thereof in spaced relation to the member to which said element is applied, said angularly offset side being resiliently yieldable and positioned to be engaged by the other member to press said free edge into sealing engagement with the member on which it is mounted.

14. A weatherstrip for a pair of members, one of which is relatively stationary and the other of which is relatively swingable, said weatherstrip comprising cooperating self-adjusting, interlocking sealing elements applicable one to each of said members, one of said elements having a substantially U-shaped fold adapted to lie intermediate said members in spaced relation to the same so as to afford free lateral movement of said fold, a second fold reversely extending relatively to said first fold and laterally spaced therefrom, the outer side of said second fold having an angularly offset portion normally disposed with the free edge thereof in spaced relation to the member to which said element is applied, said angularly offset side being resiliently yieldable and positioned to be engaged by the other member to press said free edge into sealing engagement with the member on which it is mounted, and the cooperating sealing element having a tongue adapted to be pressed into the first fold of said first mentioned sealing element.

15. A weatherstrip for a pair of members, one of which is relatively stationary and the other of which is relatively swingable, said weatherstrip comprising cooperating self-adjusting, interlocking sealing elements applicable one to each of said members, one of said elements having a substantially U-shaped fold adapted to lie intermediate said members in spaced relation to the same, a laterally offset attaching flange on one side of said fold affording lateral resilient movement of said fold, a second fold on the other side of said fold and reversely extending relatively to said first fold and laterally

- spaced therefrom, the outer side of said second fold having an angularly offset portion normally disposed with the free edge thereof in spaced relation to the member to which said element is applied, said angularly offset side being resiliently yieldable and positioned to be engaged by the other member to press said free edge into sealing engagement with the member on which it is mounted.
- 10 16. A weatherstrip for a pair of members, one of which is relatively stationary and the other of which is relatively swingable, said weatherstrip comprising cooperating, self-adjusting, interlocking sealing elements applicable one to each of said members, one of said elements having a substantially U-shaped fold adapted to lie intermediate said members in spaced relation to the same, a laterally offset attaching flange on one side of said fold affording lateral resilient movement of said fold, a second fold on the other side of said fold and reversely extending relatively to said first fold and laterally spaced therefrom, the outer side of said second fold having an angularly offset portion normally disposed with the free edge thereof in spaced relation to the member to which said element is applied, said angularly offset side being resiliently yieldable and positioned to be engaged by the other member to press said free edge into sealing engagement with the member on which it is mounted, the free edge of said angularly offset portion of the second fold being rebent on itself and serving to prevent locking of said sealing edge against its respective member when pressure of the other member on the sealing flange is relieved.
- 15 17. A weatherstrip of the class described comprising a strip of resilient material having reversely extending and laterally spaced relatively U-shaped folds, a laterally offset attaching flange on the outer side of one of said folds, and an angularly offset sealing flange on the outer side of the other of said folds, the free edge of said angularly offset sealing flange terminating adjacent the base of said first fold but laterally spaced therefrom in a direction toward the second fold, said free edge serving as a sealing edge.
- 20 18. A weatherstrip of the class described, comprising a strip of resilient material having reversely extending and laterally spaced relatively U-shaped folds, a laterally offset attaching flange on the outer side of one of said folds, and an angularly offset sealing flange on the outer side of the other of said folds, the free edge of said angularly offset sealing flange lying at the side of the first fold opposite from the attaching flange, said free edge constituting a sealing edge.
- 25 19. A weatherstrip of the class described, comprising a strip of resilient material having laterally spaced reversely extending folds therein disposed longitudinally thereof, the outer side of one fold having a laterally offset attaching flange, the outer side of another fold having an outwardly diverging sealing flange, the free edge of which constitutes a sealing edge, one end of the outer side of one fold having a rearwardly bent extension disposed on the outer side of said fold, and the outer side of another fold having a rearwardly bent extension disposed interiorly of said fold, said extensions serving as deflectors for discharging fluid substances collected thereby toward the weather side of said folds.
- 30 20. A weatherstrip construction as defined in claim 8 wherein the surface engaged by the free edge of said sealing flange comprises an escutcheon carried by one of said members and disposed for edgewise contact of said sealing flange.
